APPARATUS FOR EFFECTING SEPARATION
OF THE PARTS OF DENTURES

Alva James Vance, Beverly Hills, Calif.

Application July 17, 1936, Serial No. 91,243

3 Claims.

(Cl. 32—1)

This invention relates to apparatus for the separation of parts of denture assemblies such as gold-frame-mounted porcelain teeth, false teeth assemblies, cases, or the like, the apparatus including a heated acid bath in which separation is effected and a neutralizing bath for rendering harmless the fumes given off by the heated acid bath.

I shall describe the invention with reference to the accompanying drawing which shows by way of example three practical forms of apparatus embodying the invention. In the drawing, Figure 1 is a vertical section of one form.

Figure 2 a similar section of another form, and Figure 3 an elevation, with parts in vertical section, of a self-contained unit as the preferred embodiment of the invention.

Referring to the drawing, and first to Figure 1, reference numeral 10 designates a container, ordinarily of glass, having a bottom wall and cylindrical side walls. The mouth of the container is closed by a stopper 11 which may be of rubber or of glass with a ground fit. The stopper is apertured to pass one extremity of a U-shaped glass tube 12, the other extremity of the tube being adjacent the bottom of a container 13 which is upwardly open. Reference numeral 14 designates an acid bath in the container 10 and the bath may be of hydrochloric or other suitable acid. It is preferably of sufficient depth so that the denture assembly may be completely immersed therein. The container 13 has therein a neutralizing bath 15 which may conveniently and economically be a strong soda solution.

With the denture assembly in the acid solution, heat is applied to the boiler 10 and the heated acid acts to effect separation of the denture parts. The noxious fumes arising from the heated acid bath pass through tube 12 to the bottom of the soda bath where they are released and neutralized by the soda solution, the gases escaping at the top of the soda bath being entirely harmless.

In Figure 2 reference numeral 16 designates an acid container. Reference numeral 17 designates a stopper or plug which closes the mouth of container 16 and also the lower end of a cylindrical glass tube 18, the tube 18 and the stopper 17 constituting an upwardly open container for the soda bath. A U-shaped piece of glass tubing 19 has one end passed through stopper 17 and the other end disposed adjacent the top of stopper 17 in the soda bath. Reference numeral 20 designates a reflector bowl which has mounted therein an electrical heating element 21. The

operation of this apparatus is the same as above described.

In Figure 3, reference numeral 22 designates a flat base which is triangular in plan and may be provided with feet 23 at its corners. A vertical post 24 has its lower end secured to the base 22 and at its upper end carries oppositely and horizontally extending clamps 25 and 26 which support respectively the glass receptacles 27 and 28. An arm 29 projecting from the post 24 supports 10 a reflector bowl 30 beneath the receptacle 27, the reflector bowl having mounted therein an electrical heating element 31.

The mouth of the receptacle 27 is closed by a suitable stopper 32 which may be provided with 15 a knob 33 for convenient manipulation. A funnel 34 has a stem 35 passed through stopper 32, the stem being provided with a control valve 36. By opening the valve fluid introduced into funnel 34 may be admitted through stem 35 to the 20 interior of receptacle 27 so that the bath may be conveniently replenished or modified.

Also passed through stopper 32 is an angular piece of glass tubing 37 whose outer end is connected by a piece of rubber tubing 38 with an 25 angular piece of glass tubing 39 of which one end is passed through a stopper 40 for receptacle 28 and terminates adjacent the bottom of the latter. An angular glass tubing 41 also has one end passed through stopper 40.

The denture assembly is placed in container 27 and immersed in the acid bath therein, the bath being heated by the heating element 31 and the heat supply being concentrated by the reflector 30. During this operation valve 36 is of 30 course closed and fumes arising from the acid pass through tubes 37, 38 and 39 to the bottom of the soda bath in receptacle 28, the neutralized residues passing from the latter through vent tube 41.

The construction just described is particularly desirable since it constitutes a self-contained unit with the various parts compactly and efficiently arranged.

It will be understood that the invention may 45 be variously embodied and that accordingly I do not limit myself to the arrangements herein disclosed. Various changes in form and arrangement of parts may be made without departure from the scope of the invention as defined in the 50 following claims.

I claim:

1. A dental apparatus for effecting separation of the parts of denture assemblies, comprising a support, a closed receptacle mounted on said 55

support, a body of acid in said closed receptacle in which a denture assembly may be completely immersed, heating means supported in said base adjacent said closed receptacle whereby said acid bath is heated, a second closed receptacle mounted on said support adjacent the first closed receptacle, a neutralizing bath in said second receptacle, and means for conducting fumes from said acid bath to a point beneath the surface of said neutralizing bath so that such fumes will be discharged in said neutralizing bath to be neutralized thereby.

2. Apparatus for effecting separation of the parts of denture assemblies, comprising a base, 15 a boiler mounted on said base and having an acid solution therein in which an assembly may be immersed, a heater for said boiler mounted in said base, a receptacle mounted on said base and containing a neutralizing solution, and a connection between the boiler and receptacle where-

by acid fumes generated in the former are conducted to the latter to be treated by said neutralizing solution.

3. A dental apparatus for effecting the separation of the parts of dental assemblies, comprising a base, a glass receptacle supported on said base and closed by a stopper, an acid bath in the closed receptacle in which the denture assembly may be immersed, electric heating means mounted in said base adjacent said closed receptacle whereby the acid bath is heated, a second glass receptacle closed by a stopper and supported on said base adjacent the first closed receptacle, an acid neutralizing solution in the second closed receptacle and a connection for conveying fluid between the acid bath and the neutralizing solution whereby acid fumes generated in the former are conducted beneath the surface of the latter to be treated by said neutralizing solution.

ALVA JAMES VANCE.
